UNITED STATES PATENT OFFICE.

JOSEPH S. DRONSFIELD, OF OLDHAM, COUNTY OF LANCASTER, ENGLAND.

GRINDING APPARATUS.

SPECIFICATION forming part of Letters Patent No. 292,290, dated January 22, 1884.

Application filed September 18, 1883. (No model.) Patented in England June 22, 1883, No. 3108.

To all whom it may concern:

Be it known that I, JOSEPH STANDRING DRONSFIELD, a subject of the Queen of Great Britain and Ireland, and residing at Oldham, county of Lancaster, England, have invented 5 certain Improvements in Grinding Apparatus Having Traversing Grinders, (for which I have obtained a patent in Great Britain, No. 3,108, June 22, 1883,) of which the following 10 is a specification.

My invention relates to the apparatus employed in the grinding of carding-cylinders and cards ordinarily known as the "Horsfall" or "Hardy" roller. In the said apparatus a short cylindrical grinder is traversed to and fro upon a hollow shaft by means of an internal screw, which is cut with both right and left hand threads or grooves crossing each other. Previously to my invention only one 15 grinder has been used in each apparatus. I mount two or more grinders upon a single hollow shaft, and I cut the screw with a corresponding number of sets of screw-threads. In the ordinary apparatus the fork which 20 engages with the thread of the screw and acts as a nut cannot be removed without taking the apparatus to pieces by unscrewing one of the ends of the hollow shaft, and when the parts are put together again the shaft seldom runs 25 quite true. I so construct the grinder as that the said fork can be readily removed through the slot in the shaft without unscrewing the 30 ends of the shaft.

In the accompanying drawings, Figure 1 is 35 a longitudinal view, partly in section, of the complete apparatus. Fig. 2 is a cross-section on the line A on a larger scale, and Fig. 3 is a longitudinal section. Figs. 4 and 5 are enlarged views of the fork and its holder. Fig. 40 6 is a sectional detail view.

In the figures, *a* is the hollow shaft, which is closed at each end by means of collars upon the journals *b b'*, which are turned to revolve in the bearings on the carding-engine. The 45 ends of the shafts are tapped or chased with screw-threads, and the collars on the said journals are prepared to screw into the ends of the shaft. In the ordinary apparatus the shaft *a* is only provided with the journal *b*, the 50 other end of the shaft being closed with an annular disk, through which the inner shaft, *c*, projects and forms the other trunnion; but I

have reduced the shaft *c* in diameter, and added the trunnion *b'*, as shown in the sectional view, Fig. 6, through which the shaft passes, 55 so that the shaft *c* has a long bearing in the trunnion instead of a short bearing in the disk, as in the old arrangement. The shaft *c* extends from one end of the hollow shaft to the other, and is cut with right and left hand 60 threads *d*, which cross each other, as is usual. Upon the hollow shaft are mounted two grinders, *e e'*. The screw-shaft *c* is turned with two distinct sets of screw-threads, one set not running into another. 65

In Fig. 3, *h* is the curved shunting-groove which ends one set of threads, and *i* is the shunting-groove which begins the other set, these shunting-grooves guiding the fork from the right-hand to the left-hand threads, or 70 vice versa, as is usual. Each grinder is traversed by its own set of threads, and both move simultaneously. When one grinder—say the grinder *e'*—is at one end of the hollow shaft, as in Fig. 1, the grinder *e* will be at or 75 about the center. The rotation of the screw-shaft will move both grinders toward the right hand, the grinder *e'* moving from the left-hand end toward the center, and the other moving from the center toward the right- 80 hand end. When the grinder *e'* has reached the center, the groove *h* will shunt the fork—say, for example, from the right-hand threads into the left-hand threads—the fork of the grinder *e* being shunted at the same time by 85 means of a shunting-groove at the end of the screw-shaft, and both grinders will move toward the left-hand.

The action is similar to that of the ordinary Horsfall or Hardy grinder, with the exception 90 that the screw-shaft of the latter has no shunting-grooves in the center, and has only one grinder, which traverses from end to end of the shaft, the fork being shunted by shunting-grooves at each end of the shaft. By using 95 two grinders instead of one, I can effect the grinding more quickly, as each grinder has only to grind one-half of the width of the cylinder from one edge to the center, the other grinding from the center to the other edge, so 100 that the work can be done in about half the time usually required. The pulleys *e e'* are covered with emery, as is usual; but I prefer to mold the emery-coating into the grooved

form represented in the drawings, in accordance with my English patent, dated December 27, 1880, numbered 5,442. Each grinder consists of a metal pulley, *e*, which fits upon a turned block, *f*, and is secured thereto. The block *f* is formed with a turned flange, which fits against an internal flange on the pulley *e*, and bolts *g*, passing through both flanges, secure the parts together. A projection is formed on the block *f*, and this projection is bored to receive a turned fork-holder, *k*, which is secured in place by means of a set-screw, *m*, or by other suitable means. This fork-holder is bored to receive the shank *l* of the fork, which is formed with a crutch-head, *l*, which enters the grooves of the screw and acts as a nut, whereby the grinder is moved to and fro, as is usual. Previously to my invention the shank *l* has been fitted into a hole bored in the block *f*, which has been formed in one piece with the part *e*. The fork-holder is formed with a downward projection, *k'*, which is placed at the sides or is otherwise fitted to slide in a slot which is formed in the hollow shaft and runs nearly from end, as in the ordinary apparatus. This projection acts as a key, whereby the grinder is caused to revolve with the shaft and also supports the fork by bringing the bearing for the shank *l* close up to the crutch-head. When the fork has become much worn, so that it is desirable to replace it with a new one, or to remove it for other reasons, the pulley *e* is removed by removing the bolts and drawing the pulley of the block *f*. The set-screw *m* is then slackened and the fork-holder *k* is drawn outward until the crutch-head *l* clears the screw-grooves. The shank *l* is then turned until the crutch-head is in line with the slot in the hollow shaft, so that it can pass through the slot. The fork-holder *k* is then withdrawn, bringing with it the fork. To permit the turning of the crutch-head into line with the slot, I make the hollow shaft larger than usual, so that there is sufficient room above the screw-shaft for the crutch-head to turn after it has left the screw-groove. The diameter of the fork-holder must be great-

er than the length of the crutch-head, so that the latter will pass through the hole in which the fork-holder is fitted. The shaft might be provided with three or more grinders, the screw-shaft being cut with a corresponding number of distinct sets of screw-threads. If the screw-shaft were cut for three grinders, one set of screw-threads would be cut to move a grinder from one end to about one-third of the length of the shaft from the end, and to return the grinder to the end. The next set would be cut to work a grinder to and fro on the middle part of the shaft through about one-third of its length. The third grinder would work to and fro on the other third part of the shaft. In practice two grinders will usually be sufficient.

The method of mounting the fork for convenience of removal is applicable when only one grinder is mounted on the hollow shaft.

I claim as my invention—

1. In a card-grinding device, the combination of a hollow shaft and a screw-shaft having two separate sets of screw-threads, with shunting-grooves near the center and near the opposite ends, and two grinders each having a fork adapted to traverse one of said sets of screw-threads, all substantially as set forth. 75

2. In a card-grinding device, the combination of two or more grinders and forks therefor with a rotating screw-shaft, having a corresponding number of sets of right and left hand screw-threads, and shunting-grooves at 80 the ends of each set, substantially as described.

3. The combination of the screw-shaft and block *f* with the fork-holder *k*, adapted to an opening in said block large enough for the withdrawal of the fork, the latter having its 85 shank adapted to swivel in the said holder, substantially as specified.

In testimony whereof I have signed my name to this specification in the presence of two subscribing witnesses.

J. S. DRONSFIELD.
